US00D546067S

(12) **United States Design Patent** (10) **Patent No.:** **US D546,067 S**
Walther et al. (45) **Date of Patent:** **** Jul. 10, 2007**

(54) **PAPER PRODUCT**

(75) Inventors: **Rachael Eden Walther**, Union, KY (US); **Douglas Jay Barkey**, Maineville, OH (US)

(73) Assignee: **The Procter + Gamble Company**, Cincinnati, OH (US)

(**) Term: **14 Years**

(21) Appl. No.: **29/261,675**

(22) Filed: **Jun. 16, 2006**

(51) **LOC (8) Cl.** **05-06**

(52) **U.S. Cl.** **D5/37; D5/57; D5/25**

(58) **Field of Classification Search** ..... **D5/1-3, D5/5, 7-8, 11, 13-16, 19-20, 23-28, 30, D5/32, 35-37, 39, 43, 45, 47, 49-50, 52-66, D5/99; D2/749, 994; D6/582-583, 595-596, D6/598, 608, 603-606, 613, 616, 617, 619, D6/622; 428/17-18, 151, 154, 156, 171, 428/187, 198, 199, 540, 542.2, 542.6, 919, 428/904.4; D24/124, 125, 126; D25/142, D25/152; 5/413 AM, 709; 162/134, 140, 162/109, 231; 156/148, 209; D7/396.4-5**

(57) **CLAIM**

The ornamental design for a paper product, as shown and described.

DESCRIPTION

The sole FIGURE is a top plan view of a paper product showing our new design.

The broken lines shown along the border of the FIGURE depict the boundaries of one repeat unit of the claimed design and indicate that the design may continue indeterminately in one or more directions. The broken lines form no part of the claimed design.

1 Claim, 1 Drawing Sheet
